MECHANICAL CLASSIFIER

Ralph J. Hall, Lead, S. Dak.

Application January 25, 1938, Serial No. 186,885

2 Claims. (Cl. 209—158)

The present invention relates to improvements in a mechanical classifier and more particularly to the type useful for separating solid or sand particles from slimes or slurries containing the same.

An object of the invention is to provide a device for the mechanical separation of sand or coarse particles from sand-slime pulp in a more economical and efficient way than has been heretofore known.

Another object is to provide a device of small size relative to its capacity and which requires a minimum of power and wash water to operate.

Another object is to provide a device in which the only moving parts are slowly driven scrapers.

A further object is to employ an air and/or water lift to cause the movement of liquid in the classifier.

A still further object is to provide a method for classifying particles contained in sand-slime pulp which comprises confining the slimes to the upper or settling chamber and admitting only the sludge settled out of the slimes to the lower or wash chamber.

In general, the device has two chambers, one of which is settling chamber and the other a washing chamber. The settling chamber is disposed above the washing chamber and communicates therewith through a restricted opening. Sand-slime pulp is introduced into the settling chamber and the sludge accumulating on the bottom of the chamber is scraped to the restricted opening which communicates with the washing chamber. When the device is in operation the amount of sludge passing through the restricted opening prevents substantial amounts of slime from entering the wash chamber. In the wash chamber the sludge drops by gravity and is met by a counter-current of wash water which cleans the particles to be recovered. The heavier particles continue against the wash counter-current and fall directly to the bottom of the wash chamber from whence they are withdrawn. The washings include the lighter particles. The counter-current of wash water drives the washings into a well in the wash chamber and air admitted into the well serves to drive the washings up through a duct into the settling chamber. The washings are allowed to settle along with the incoming slimes and further of the particles are recovered therefrom. The washings also act to dilute the slimes and make it easier to separate the heavy particles in the settling chamber.

The waste liquid is collected from the set-

ting chambers by means of a launder which receives the upper or lighter portion of the liquid after it has settled in the settling chamber.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a central vertical section taken on the line 1—1 of Figure 2.

Figure 2 is a horizontal section taken on the line 2—2 of Figure 1.

Figure 3 is a horizontal section taken on the line 3—3 of Figure 1.

Figure 4 is an enlarged detail view in section taken on the line 4—4 of Figure 3.

Figure 5 is a fragmentary central vertical section taken on the line 5—5 of Figure 2, and

Figure 6 is an enlarged detail view partly in section taken through the gland of the scraper drive shaft.

Referring now to the drawings and particularly to Figure 1, 10 designates a tray which forms the settling chamber of the classifier. The tray is shown in the form of a truncated cone but it may also be flat. At the periphery of the tray 10 is placed a launder 11 over the lip 12 of which liquid can flow. At one or more points in the launder 11 outlet pipes 13 are placed for the purpose of discharging a liquid which overflows the lip 12. The center of the tray 10 is open and communicates with a cylindrical vessel 14 which forms the washing chamber of the classifier.

The settling chamber formed by the tray 10 is to provide a great bottom area and the tray is therefore quite shallow in proportion to its diameter. The wash chamber formed by the cylindrical vessel 14 is, on the other hand, designed to secure a substantial vertical dimension. The vessel 14 is also shown provided with a conical bottom to assist in collecting the particles which settle thereon. The central part of the bottom of the vessel 14 is open and is provided with an outlet nozzle 15 which has a gate valve 16 thereon.

A vertical shaft 17 is suspended through the central opening of the settling tray 10 upon an upper bearing 18 and a lower bearing 19 which are suitably supported as by attachment to the building or the like. The shaft 17 has, between the bearings 18 and 19, a flanged pulley 20 which is driven from a power source having a pulley 25

21 through the medium of a belt 22. At the level of the settling tray 10, the shaft 17 has a spider 23 keyed thereto, as best shown in Figure 2. The spider has four radially extending sockets each of which receives an arm 24 which carries a plurality of depending plows or scrapers 25. The plows or scrapers 25 are adapted to travel close to the bottom of the tray 10 when the shaft 17 is rotated. The plows or scrapers 25 are disposed angularly with respect to the arms 24 so that, when the shaft 17 is rotated clockwise as seen in Figure 2, sludge on the bottom of the tray 10 will be moved toward the center of the settling chamber. Of course, it will be seen that other forms of scraper blades may be used in place of the angularly disposed plows shown.

At the lower end of the shaft 17, as shown in Figures 1 and 3, is keyed a second spider 26 which likewise has four radial sockets receiving arms 27 which carry angularly disposed plows or scrapers 25'. The spider 26, arms 27, and scrapers 25' are smaller than those in the settling tray and they are adapted to scrape settled particles from the bottom of the washing chamber into the nozzle 15 when the shaft 17 is rotated.

A feed well is formed at the center of the settling tray by a box 28, of generally cylindrical form, which is supported by a bracket 29 secured to the support 30 which holds the lower bearing for the shaft 17. The top of the box 28 is provided with a central opening through which passes the shaft 17, and a side opening 31 which receives the discharge end of a feed pipe 32. As shown by the dotted liquid level lines in Figure 1, the sides of the box 28 extend down below the surface of liquid in the settling chamber. There is, therefore, a constant supply of incoming liquid for the settling chamber so that the flow is even and uniform and the settling material will not be disturbed by the admission of fluid.

Above the spider 23, on the shaft 17, is keyed a feed apron 33 the peripheral portion of which extends downwardly and under the edges of the box 28. A number of guides 34 are located on the edges of the feed apron and extend up and against the inner side of the box 28. The feed apron 33 causes the incoming liquid to flow radially outwardly into the settling chamber and prevents direct flow of this incoming liquid down through the central opening of the tray 10.

Below the spider 23, as seen in Figure 5, is an air reservoir 35 which is an inverted cylindrical vessel having an outwardly flaring skirt portion at the bottom. As shown in Figure 6, the upper wall of the reservoir 35 is held to the shaft 17 through a clamp having an upper male member 36 and a lower female member 37. The female member contains packing which is adapted to be tightened against the shaft 17 when the bolts 38 are taken up. This maintains an air-tight joint below the surface of the liquid in the settling chamber. Between the feed apron 33 and the air reservoir 35 are placed a number of vertical pipes 39 which pass through the flange of the spider 23, as shown in Figure 2, and which extend above the level of liquid in the feed chamber and extend down a substantial distance into the air reservoir. The pipes 39 may be threaded into nuts 40 secured to the feed apron so as to permit vertical adjustment of the pipes. Of course, the joints of the pipes 39 with the reservoir 35 are made air-tight to prevent leakage of air from the reservoir.

An air supply pipe 41 connected to a source of compressed air extends up into the air reservoir 35 above the bottom of the pipes 39.

Around the outside of the vertical washing chamber are placed two circular wash water feed lines 42 and 43 respectively. These feed lines connect with nozzles 44 which extend through the sides of the vessel 14 and are directed upwardly and centrally of the wash chamber. The nozzles are directed substantially at the air reservoir 35. Each of the nozzles 44 is provided with a valve 45 which permits obtaining the desired pressure in the counter-current of wash water produced. Figure 4 shows the connection between one of the feed pipes 43 and one of the nozzles 44. The valve 45 is connected through a nipple 46 to the feed pipe 43. A short nipple 47 on the opposite side of the valve connects with a length of rubber or other flexible hose 48. A short nipple 49 in the opposite end of the rubber hose 48 connects to a nut 50 which passes through the wall of the vessel 14. The rubber hose 48 will be secured to the nipples 47 and 49 respectively by means of hose clamps 51 of well known type. On the interior of the vessel 14 the nozzle 44 is connected to the nut 50 by means of the coupler 52.

In operation, sand-sludge pulp or slurries containing heavy particles worth recovering are admitted through the feed pipe 32 into the top of the feed box 28. The liquid flows down upon the apron 33 and radially outward to fill the settling tray 10. The wash chamber comprising the vessel 14 will be filled with clear wash water admitted through the nozzles 44. The incoming feed liquid will not pass down into the wash chamber to any substantial extent. In the relatively quiet settling tray 10 heavy particles together with entrained slime and waste fall to the bottom of the tray 10 as a thick sludge. The lighter fluid rises to the top of the tray 10 and overflows the lip 12 into the launder 11 from which it is removed through the pipe 13. The shaft 17 is being revolved and the scrapers 25 move the deposited sludge along the bottom of the tray 10 toward the narrow annular gap 53 which exists between the side of the air reservoir 35 and the bottom of the tray 10. The sludge falls by gravity down through the opening 53 and is directed toward the nozzles 44 by the outflaring skirt of the air reservoir. This sludge consists of heavy particles and also of lighter particles both types of which are surrounded and contaminated by the slime. As the sludge drops towards the nozzles 44 wash water emerging from the nozzles produces a strong washing counter-current which tears the slime from the particles. The heavy particles fall by gravity through the counter-current while the lighter washed particles are driven centrally and upwardly of the vessel.

In the meantime, air has been admitted through the pipe 41 into the air reservoir 35 from which it displaces a part of the liquid. As further quantities of air are introduced the liquid level is driven down until the air can escape upward through the pipes 39 into the feed box 28. Due to the violent nature of the escape of air up through the pipes 39 quantities of the liquid in the lower part of the air reservoir are carried up through the pipes 39 with each surge of the air. The escape of air through the liquid likewise causes a great deal of agitation in the liquid which greatly assists the separation of the heavy particles from the entrained slime. The

washings which consist of slime together with the lighter particles pass upwardly through the pipes 39 into the feed box 28 in which they mix with the incoming feed solution and pass into 5 the settling tray 10. The slime being light rises to the top of the liquid in the tray 10 and overflows the lip 12 into the launder. Light particles are thus kept out of the product and eventually find their way into the launder 11 and are removed 10 along with the other washings.

The scrapers 25 collect the heavy particles at the bottom of the vessel 14 into the discharge nozzle 15 from which they may be removed by the opening of the valve 16. The product consists 15 only of heavy clean particles. The lighter particles, slime, wood chips and other contaminating substances are washed away into the launder 11.

The apparatus above described permits the obtaining 20 of the objects previously stated and provides means for mechanically classifying or separating heavy particles from sand-slime pulp with the minimum amount of power and wash water. The only moving parts are the scrapers 25 at the bottoms of the two chambers and these are driven at a speed of from 1 to 3 revolutions per minute. Movement of liquid from the wash chamber to the settling tray is accomplished without friction by the use of the air lift. Wash 30 water and washings are mixed with the incoming liquid to dilute it and dispose it for settling in the tray 10. All washings are removed through the single launder 11. The entering liquid is substantially excluded from the wash 35 chamber by the provision of a narrow angular opening 53 which constitutes the only communication for liquids between the chambers, aside from the air lift. The sluge falling through the opening 53 passes directly into the current from 40 the nozzles 44 and is driven thereby, or tends to be driven up into the air reservoir. The coarser particles are of sufficient weight to overcome the washing current and fall through it to the bottom of the vessel 14.

Lighter particles, slime and undesirable impurities of low density are driven up into the air reservoir and cast up into the feed box 28 ending up eventually in the launder. The device is designed for continuous operation at high 50 efficiency and low cost. It is of small size and delivers a uniform product. No intermediate size product is produced since the only particles that can be recovered are those of sufficient weight to fall through the washing counter-current thrown by the nozzles 34. Of course, for 55

classifying different weight particles the force of the washing current flowing from the nozzles 44 may be varied by the adjustment of the valves 45.

It is obvious that various changes and modifications may be made in the details of construction and design of the above specifically described embodiment of this invention without departing from the spirit thereof, such changes and modifications being restricted only by the scope of the following claims.

What is claimed is:

1. A classifier comprising a settling chamber with a tray of relatively large bottom area, a washing chamber of substantial depth disposed beneath said settling chamber, means for introducing liquid containing materials to be classified into said settling chamber, said tray communicating with the upper part of said washing chamber through an annular restricted opening in the bottom thereof, means for collecting heavy settled material in said tray and moving the same into said annular opening, whereby the heavy material falls into said washing chamber, a plurality of spaced wash nozzles disposed circumferentially about said washing chamber and directed upwardly to produce a wash counter-current of liquid adapted to strike the heavy material entering the washing chamber from the settling chamber, and means in the upper part of said washing chamber for collecting the washings and elevating the same to said settling chamber.

2. A classifier comprising a settling chamber, a washing chamber disposed beneath said settling chamber, said chambers communicating through an opening in the bottom of said settling chamber, means for introducing liquid containing materials to be classified into said settling chamber, means for collecting heavy settled materials in the settling chamber and moving the material to said opening in the bottom of said settling chamber, means for restricting the opening in said settling chamber to cause the heavy settled materials to fall into the washing chamber in a relatively narrow stream, washing means including nozzles directed upwardly to throw a washing current of liquid against the heavy materials falling through said washing chamber, and means for receiving the washing current in the upper part of said washing chamber and for elevating the liquid and washings carried by said current to the said settling chamber.

RALPH J. HALL.
